Peter Schladermundt, Bronxville, N. Y., and Charles L. Metzler, Palisades Park, N. J., assignors to Valley Upholstery Corp., New York, N. Y., a corporation of New York

Application August 20, 1948, Serial No. 148,198

Term of patent 14 years

(Cl. D15—1)

To all whom it may concern:

Be it known that we, Peter Schladermundt and Charles L. Metzler, citizens of the United States, residing at Bronxville, New York, and Palisades, Park, New Jersey, respectively, have jointly invented a new, original, and ornamental Design for a Chair, of which the following is a specification, reference being had to the accompanying drawings, forming part thereof, in which:

Fig. 1 is a side perspective view of a chair embodying our new design;

Fig. 2 is a top plan view thereof;

Figs. 3 and 4 are sectional views taken substantially on lines 3—3 and 4—4 of Fig. 1;

Fig. 5 is a sectional view taken substantially on line 5—5 of Fig. 2; and

Figs. 6, 7 and 8 are a front, side and rear elevational views, respectively, of the chair shown in Fig. 1.

We claim:

The ornamental design for a chair, as shown.

PETER SCHLADERMUNDT.
CHARLES L. METZLER.
